C. F. BOTTO,
TUBE CUTTING AND THREADING TOOL.
APPLICATION FILED SEPT. 20, 1916.

1,216,772.

Patented Feb. 20, 1917.

UNITED STATES PATENT OFFICE.

CHARLES F. BOTTO, OF PHILADELPHIA, PENNSYLVANIA.

TUBE CUTTING AND THREADING TOOL.

1,216,772.

Specification of Letters Patent. Patented Feb. 20, 1917.

Application filed September 20, 1916. Serial No. 121,138.

To all whom it may concern:

Be it known that I, CHARLES F. BOTTO, a citizen of the United States, residing in the city and county of Philadelphia, State of Pennsylvania, have invented a new and useful Tube Cutting and Threading Tool, of which the following is a specification.

My invention consists of a device adapted to cut metallic tubes (or rods) with screw-threads thereon, or to cut them through to sever the same. To this end, the device is equipped with a two part cutter of reversible nature, and means for interlocking certain members of the device, whereby only the operations of screw-threading or the severing may be effected, without interfering with each other.

The invention is satisfactorily illustrated in the accompanying drawing, but the important instrumentalities thereof may be varied, and so it is to be understood that the invention is not limited to the specific details shown and described.

Figure 1 represents a top plan view of a screw-threading and severing device embodying my invention.

Fig. 2 represents a longitudinal vertical section thereof on line 2—2 Fig. 1.

Fig. 3 represents a bottom plan view thereof.

Fig. 4 represents a longitudinal vertical section of a portion on line 4—4 Fig. 2.

Fig. 5 represents a longitudinal vertical section of a portion on line 5—5 Fig. 1.

Fig. 6 represents a perspective view of the two part cutter employed.

Fig. 7 represents a side elevation of a portion of the members shown in Fig. 4.

Similar numerals of reference indicate corresponding parts in the figures.

Referring to the drawings:

1 designates the stock of the device, the same consisting of the open frame 2 through which the tube 3 may be passed, one side of said frame having therein the internally threaded boss 4 in which is fitted the screw 5, the inner end whereof is swiveled to the forked head 6, which latter serves to engage said tube and clamp it firmly to said frame.

The stock 1 has thereon the handle 7 for holding the same, and the screw 5 has thereon the handle 8 for rotating the same as is evident.

On the frame 2 is the plate 9 which is secured thereto by the screws 10, and having on the central portion thereof the annular

flange 11 which freely embraces the shoulder 12 on the base of the rotatable sleeve or cylinder 13, which rests freely on the top walls of the frame 2, the tube 3 being adapted to 60 pass through said sleeve.

On the side of the plate 9 and flange 11 is the member 14 forming a guide for the spring-pressed plunger or pin-like member 15 whose inner end is adapted to pass 65 through said flange and interlockingly enter the recess 16 in the adjacent portion of the sleeve 13, so as to prevent rotation of the latter when required.

Projecting from the side of said plunger 70 15 is the finger 17, and in the member 14 is the slot 18 into which when the plunger is drawn out said finger may be entered, whereby the plunger is held disconnected from the sleeve 13 when the latter may be 75 rotated when required.

When the plunger is rotated in the proper direction, the finger 17 is removed from the slot 18 and the spring of the plunger forces the latter into the recess 16, thus again locking the sleeve 13 against rotation.

The exterior of the sleeve 13 is screw-threaded for engagement with the interiorly screw-threaded sleeve or cylinder 19 on which said sleeve 13 is rotatable and so may 85 be raised and lowered thereon, or vice versa.

It is to be understood that the base of the cylinder rests freely on the top wall of the frame 2, and to this frame is connected by the screws 10 the annular flange 11 which 90 freely embraces said shoulder, see Fig. 2.

The flange 11 is carried by the plate 9, said plate having on its opposite sides elongated slots 9^a which receive bosses 2^a rising from the frame 2, by which provision the cylinder 13 and connected parts may be moved to the right and left for centering tubes and rods in said cylinder 13 of different diameters, the screws 10 when tightened thus serving to retain said cylinder in adjusted 100 position, without liability to turn.

On the side of said sleeve 19 is the boss 20 in which is the slid able cutter carrier 21 which is tubular and engaged by screw 22 in the interior thereof, said screw being swiveled in said boss and provided with the head 23, whereby said screw may be rotated to cause the carrier 21 to move in and out of the boss 20. On the inner end of the carrier 21 in a slot therein, see Figs. 4 and 105 7, is mounted by the pivot 24 the reversible two part cutter 25, one cutting edge 26 of

which is adapted for cutting a screw thread on a tube, and the other cutting edge 27 of which is adapted for cutting through or severing a tube, it being evident that by 5 properly advancing the carrier 21 in the boss 20, the cutter 25 may be turned so as to present either of its cutting edges to the tube outside of the boss 20, while the other cutting edge remains in the boss preventing rotation of said cutter.

10 The boss is provided with a screw 28 whose point freely enters the longitudinally extending slot or way 29 in the carrier 21 preventing rotation of the latter, see Fig. 4.

15 It will now be seen that as the sleeve 13 is held interlocked with the stock 2 and consequently with the handle 7, said sleeve may be rotated by the latter on the sleeve 19. Then the sleeve 13 is rotated and the cutter 20 21 is forced in to the required extent by the operation of the head 23 of the screw 22, and so the cutting edge 26 cuts on the tube a screw thread as shown at 30, Fig. 2.

25 When the sleeve 19 is lowered to full extent, it is frictionally held on the sleeve 13. Then the plunger 15 is drawn out, thus unlocking the sleeve 13. The cutter 25 is reversed whereby its edge 27 is presented to the tube. The sleeve 19 is now rotated, and 30 the sleeve 13 rotates with it as one, when said cutter is moved in to the required extent by the operation of the head 23 so as to cut through the tube, and so sever the same, as shown in Fig. 5.

35 In order to assist in centering the tube, I employ the ring 31, the opening of which may be varied to suit tubes of different diameters, said ring being located in the cylinder 19 and embracing the adjacent portion of 40 the tube, as most plainly shown in Fig. 2, the effect of which is evident.

Attention is directed to the fact that the forked head 6 which acts as a clamp or vise like jaw, acts to center the tube (or rod) 45 which is engaged therewith and is applicable to tubing and rods of different diameters working effectively therewith.

Having thus described my invention what I claim as new and desire to secure by Letters Patent, is:—

1. In a tube threading and severing device a primary cylinder and an auxiliary cylinder movable thereon, said cylinder having engaging screw threads, a two part reversible cutter on said auxiliary cylinder, and means on the device adapting said auxiliary cylinder to be rotated with said primary cylinder for severing purposes, or independently thereof for threading purposes.
2. In a tube threading and severing device, a primary cylinder, a support therefor, means for interlocking and disengaging said cylinder from said support, an auxiliary cylinder movably fitted on said primary cylinder, a two part reversible cutting mem-

ber, and a carrier on said auxiliary cylinder for said cutter.

3. In a tube threading and severing device, a primary rotatable cylinder, a support therefor, a member on said support adapted to engage said cylinder, and interlock it with said support and to disengage it from said cylinder to release the latter from said support and a reversibly mounted cutter.

4. In a tube threading and severing device, a primary rotatable cylinder, a support therefor, a member which is guided on said support and adapted to engage said cylinder, and means on said member and support adapted to hold said member free of said primary cylinder and a reversibly mounted cutter.

5. In a tube threading and severing device, a rotatable cylinder, a cutter, a movable carrier for said cutter, a boss on said cylinder containing said carrier, and means on said carrier and boss for operating said carrier in opposite directions, said cutter having cutting and severing cutting edges and being reversibly mounted on said carrier.

6. In a tube threading and severing device, a primary sleeve, a support therefor, an auxiliary sleeve fitted movably thereon, a cutter, and a carrier on said auxiliary sleeve for said cutter, said cutter having threading and severing cutting edges and being reversibly mounted on said carrier adapting the edges to be presented to the object to be threaded or severed.

7. In a tube threading and severing device, a primary cylinder, a support therefor, means for connecting said sleeve with said support and disconnecting it therefrom, an auxiliary cylinder fitted movably on said primary sleeve, a reversibly mounted threading and severing cutter, a carrier for said cutter on said auxiliary cylinder, and means on said carrier for operating said carrier to move said cutter to and from the object to be screw threaded or severed.

8. In a tube threading or severing device, a stock, a cutting member adapted to be carried on said stock, and a self-centering vise-like jaw and a tube embracing ring adapted to engage a tube to be threaded or severed.

9. In a tube threading and severing device, an open frame, a movable cylinder, means for adjusting said cylinder to tubes of different diameters, and a jaw-like vise adapted to embrace the tube and acting in conjunction with means carried by said frame for centering the tube on said frame.

10. In a tube threading or severing device, an open frame, a self-centering vise-like jaw therein, and a movable cylinder laterally adjustable on the frame of the device, and a ring in said cylinder adapted to embrace a tube to be threaded or severed and

acting in conjunction with said jaw in centering the tube.

11. In a tube threading and severing device, an open frame, a movable cylinder, means for adjusting said cylinder to tubes of different diameters, and a ring in said cylinder adapted to embrace the tube and acting in conjunction with means carried by said frame for centering the tube, and a plate on said frame having a flange adapted to engage a shoulder on the cylinder and laterally adjustable with the latter. 20

12. In a tube threading and severing device, an open frame, a movable cylinder, 15 means for adjusting said cylinder to tubes

of different diameters, a ring in said cylinder adapted to embrace the tube and acting in conjunction with means carried by said frame for centering the tube, a plate on said frame having a flange adapted to engage a shoulder on the cylinder and laterally adjustable with the latter, said plate and said frame having coöperating slots and bosses respectively, and means for securing the cylinder in adjusted position.

CHARLES F. BOTTO.
